UNITED STATES PATENT OFFICE.

JOHN H. COOK, OF WASHINGTON, DISTRICT OF COLUMBIA.

VEHICLE-CLEANING DEVICE.

SPECIFICATION forming part of Letters Patent No. 447,446, dated March 3, 1891.

Application filed March 18, 1889. Serial No. 303,764. (No model.)

To all whom it may concern:

Be it known that I, JOHN H. COOK, a citizen of the United States, residing at Washington, in the District of Columbia, have invented certain new and useful Improvements 5 in Vehicle-Cleaning Devices, of which the following is a specification.

My invention relates to devices for cleaning vehicle-wheels; and it consists in a novel 10 construction and arrangement of parts, as hereinafter set forth and claimed.

Figure 1 is a perspective view showing my improved cleaner in use; Fig. 2, a longitudinal sectional view of the same; Fig. 3, a trans- 15 verse sectional view showing a modification of the arrangement for securing the cleaning devices proper; Fig. 4, a horizontal sectional view on the line 4-4 of Fig. 2; Fig. 5, a top plan view showing a slightly-modified construction 20 and arrangement; Fig. 6, a transverse sectional view of the same, and Figs. 7 and 8 views illustrating further modifications.

A indicates an oblong water-box, which is curved on the arc of a circle, so as to conform 25 to a greater or less degree to the curvature of the wheel, said box being divided by a horizontal partition *a* into two chambers *b* and *c*, as shown in Figs. 2, 3, 4, 6, and 7, the bottom wall of the chamber *c* being provided with 30 perforations, as also shown in said figures. The box or chamber will advisably, though not necessarily, be provided with rollers *d*, as shown in Figs. 2, 3, 6, and 7, which are designed to rest upon the tire of the wheel and 35 prevent the wear of the plate and to allow the wheel to run as freely as possible, there being one of such rollers at each end of the box.

At its receiving end the box A is provided with a threaded neck or nipple *e*, which is 40 adapted to receive or be connected with a hose B or other source of water-supply, the water being diverted into the upper or lower chamber, according to the direction in which the valve C is turned.

Instead of arranging the valve C with its 45 axis vertical, as represented in Figs. 1, 2, and 4, it may be arranged horizontally or in any other manner desired, provided, however, that it be so constructed as to divert the water into 50 either one of the channels *b* *c* at will. It will be noticed, upon reference to Fig. 2, that the

lower chamber *c* is closed at its end, and consequently all of the water which enters said chamber must pass out through the perforations in the bottom wall thereof. The upper 55 chamber *b* is provided with a threaded nipple *f*, which is adapted to receive a nozzle D. (Shown in Fig. 1.)

The box A is provided with a handle E, which may be cast integral with the box or 60 be made separate therefrom, as preferred; and it will be seen that by taking hold of the handle and turning the cock or valve C, so as to direct the water into the upper chamber *b*, the cleaner can be lifted off the wheel and 65 the water discharged through the nozzle D to wash off the body of the vehicle.

F F' F² F³ indicate brushes or equivalent cleaning devices, which are arranged parallel with the box A, as shown in Figs. 1, 2, 3, 5, 6, 70 7, and 8, so as to act against the sides of the rim or felly of the wheel. The cleaning devices F are held in place by means of supporting-arms G, which, in the construction 75 shown in Figs. 1 and 2, are carried in undercut grooves or seats cast in the top of the water-box A. The inner ends of the supporting-arms G are turned upward and connected by means of an adjusting-screw H, so that the arms may be adjusted closer together or 80 farther apart, as desired, to carry the brushes toward or away from the sides of the wheel. If it is desired to provide for further adjustment of the brushes, the arms will be made in two parts G' G², the horizontal part G' being slotted to receive a thumb-screw I, carried by the vertical portion G², such a construction being shown in Fig. 3.

In Fig. 5 the arms G² are shown as cast integral with the box A and threaded to receive 90 clamping-screws I, which pass through slotted arms G⁴, secured to the cleaning devices F'. The cleaning devices represented in this figure are composed of chamois-skin, with suitable backing of wood, which may obviously 95 be substituted for the brushes shown in Figs. 1, 2, 3, and 7.

In Fig. 6 the cleaning devices F² are represented as composed of a backing of wood and a facing *g* of rubber, while in Fig. 7 the supporting-arms G⁵ may be made also to serve as 100 the axes or shafts of the rollers *d*, the clean-

ing devices being adjustable upon the arms G^5 to compensate for the wear and for the different widths of fellyes.

In Fig. 8 I have shown as a substitute for 5. the cleaning devices represented in the other figures a stick wrapped with cloth, which may be secured to the sides of the box A by means of spring-arms G^6 or in any other convenient manner.

10. In using this device the wheel is first raised off the ground, so as to turn free, and the box placed upon the tire of the wheel. The wheel is then rotated rapidly and the valve C turned so as to admit water into the lower chamber c , from which it escapes through the perforations in the bottom wall thereof. The water runs through the perforations in the bottom of the chamber c and moistens the mud or dirt adhering to the sides of the felly, from 15 which it is removed by means of the brushes or equivalent cleaning devices shown in the drawings, the device being steadied in position by means of the handle.

The brushes or equivalent cleaning devices 20 are so arranged as to be readily removed to allow of the substitution of new cleaners.

The box A may be made of cast-iron or of any other suitable material. It is obvious that the box need not be curved, and it is also obvious that the perforations need not necessarily be made in the bottom wall of 30 the chamber c , as it is apparent that they may be made in the side walls of said chamber alone, or in the side walls and the bottom 35 walls both, as in Fig. 3. So, too, it will be apparent that the cleaning devices need not be applied to both sides of the box, as good results could be secured by applying them to one side only; but such an arrangement necessitates a reversal of the device in order 40 to clean the inner and outer faces of the felly.

Having thus described my invention, what I claim is—

45. 1. In a device for cleaning vehicle-wheels,

the combination, with a water-box adapted to rest upon the periphery of a wheel and provided with perforations, of a cleaning device extending downward from the side of the box in position to clean the side face of 50 the felly, all substantially as shown.

2. In a device for cleaning wheels, the combination, with a perforated box, of cleaning devices applied to the sides of the box and adjustable one in relation to the other, substantially as shown, whereby the space between the cleaning devices may be varied to suit different-sized wheels. 55

3. In a device for cleaning wheels, the combination, with a perforated box provided with 60 laterally-extending arms, of cleaning devices carried by the arms, and means, substantially such as shown, for varying the space between the cleaning devices.

4. In a device for cleaning wheels, the combination, with the box A, provided with perforations in its lower face, of a cleaning device applied to the side of and adapted to act in conjunction with the box, and rollers secured to the under side of the box, substantially as 70 shown. 65

5. In combination with a box A, provided with separated chambers b c , the latter closed at one end, a valve C, adapted to direct the water into either of the chambers at will, and 75 a cleaning device applied to the side of the box, as and for the purpose set forth.

6. The box A, provided with threaded nipples e and f , and the separated chambers b c , perforations in the bottom wall of chamber 80 c , a valve C, adapted to direct water into either of the chambers b c at will, and a cleaning device applied to the side of the box.

In witness whereof I hereunto set my hand in the presence of two witnesses.

JOHN H. COOK.
